INSECT SHIELD FOR DOORS

Thomas W. Seifres, Dumas, Ark.

Application August 30, 1944, Serial No. 551,903

5 Claims. (Cl. 160—18)

1

This invention relates to an insect shield for doors, and more particularly to a screen door so designed as to reduce the tendency of insects to enter a building when the door is open.

A primary object of this invention is the provision of an improved screen door having an auxiliary section associated therewith, and simultaneously openable with the door, designed to prevent the direct passage of insects through the door when the same is open.

A further object is the provision of such a door as set out in the foregoing object, of improved means for opening the doors simultaneously.

A still further object is the provision of a screen door of improved insect resistant design.

Still further objects will in part be obvious and in part be pointed out as the description of the invention proceeds and shown in the accompanying drawing, wherein there is disclosed a preferred embodiment of this inventive concept.

In the drawing:

Figure 1 is a front elevational view of one form of screen door embodying this inventive concept.

Figure 2 is a top elevational view of the door shown in Figure 1.

Figure 3 is a fragmentary side elevational view showing certain details of construction, and

Figure 4 is a sectional view taken substantially along the line 4—4 of Figure 1, as viewed in the direction indicated by the arrows.

Like reference numerals refer to like parts throughout the several views of the drawing.

Having reference now to the drawing, a door frame 10 of conventional design set in any desired location in a building, has secured thereto as by hinges 11 a screen door including a frame 12 having apertures therein and screening 13 in the apertures. Door 12 is adapted to close a substantial area of door frame 10, but not the entire space surrounded by the door frame. A second supplemental screen door 13 is hinged as by hinges 14 to the opposite side of the door frame, door 13 in conjunction with door 12 being adapted to completely close the door frame. A suitable handle 15 is provided on door 12 to facilitate opening of the same.

It is to be noted that the doors open outwardly in opposite directions due to the fact that the hinges 14 and 11 are set on opposite sides of the frame.

Means are provided whereby when door 12 is opened, door 13 simultaneously opens. Such means take the form of a bracket 16 secured to the upper portion of the frame of door 12, and provided with a lug 17 extending upwardly above

2

the upper extremity of the door to which is secured, as by means of an adjustable nut and bolt connection 18, a cord 19. Cord 19 extends to and around a pulley 20 secured to door frame 10 at a point above and adjacent door 13 and thence extends forwardly to a bracket 21 secured to and extending outwardly from door 13, being secured to the upper frame thereof.

As best shown in Figure 2, suitable springs of conventional type 23, and 24, are secured to the door frame and doors 12 and 13, respectively, to provide for their return to closed position after they are opened.

From the foregoing it will now be readily apparent that as door 12 is opened, either by pressure from the inside of the building, or by the operation of handle 15, cord 19 will act about pulley 20, on bracket 21 to simultaneously open door 13, thus providing an adequate space for the passage of persons to and from the building. However, as the door 12 is opened outwardly insects and so forth on the wall of the building adjacent the door will not be driven inwardly through the door by the passage of the body of a person therethrough but will be blocked and deflected by the partially opened door segment 13, which will turn them from their course into the interior of the building and guide them along the outside wall.

From the foregoing it will now be seen that there is herein provided an improved screen door which accomplishes all the objects of this invention and others including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

1. An insect excluding screen door comprising a door frame including a pair of jambs, a screen door hinged to a first jamb and extending partially to the second jamb, a screen insect baffle hinged vertically to said second jamb and being complementary with said screen door to selectively close the door frame and means connecting said door and said baffle for causing opening of said baffle upon opening movement of said door.

2. An insect excluding screen door comprising a door frame including a pair of jambs, a screen door hinged to a first jamb and extending par-

cially to a second jamb, a screen insect baffle hinged vertically to said second jamb and being complementary with said screen door to selectively close the door frame and means connecting said door and said baffle for causing opening of said baffle upon opening movement of said door, said baffle having an outwardly pivoting movement for sweeping away insects as said door is opened.

3. The combination of claim 1, said means comprising an arm on said door and an arm on said baffle, and a flexible cable having one end secured to said arm on said door and the other secured to said arm on said baffle, and a pulley secured to said frame and guiding said cable intermediate its ends.

4. The combination of claim 3, said means being disposed outside and above said doorway to permit freely opening said door and said baffle without hindrance from said means.

5. The combination of claim 4, and adjustable

means including a screw threaded fastener on said cable engageable with said door for attaching said cable to said door.

THOMAS W. SCIFRES.
